Primary Examiner — Sharon S Oum(74) *Attorney, Agent, or Firm* — McGarry Bair PC(57) **CLAIM**

The ornamental design for a combination ceiling fan motor housing and light kit as shown and described.

DESCRIPTION

FIG. 1 is a top perspective view of a combination ceiling fan motor housing and light kit in the environment of a ceiling fan, showing my new design;

FIG. 2 is a top perspective view thereof with the ceiling fan environment removed;

FIG. 3 is a top view thereof;

FIG. 4 is a bottom view thereof; and,

FIG. 5 is a front side view thereof.

Portions of the combination ceiling fan motor housing and light kit, and the ceiling fan environment shown in broken lines form no part of the claimed design.

1 Claim, 5 Drawing Sheets(56)
